UNITED STATES PATENT OFFICE.

BERNARD LIBERMAN, LEON LIBERMAN, AND WILLIAM M. REICHART, OF PHILADELPHIA, PENNSYLVANIA; SAID LEON LIBERMAN AND SAID REICHART AS-SIGNORS TO SAID BERNARD LIBERMAN.

CIGAR-BUNCHING MACHINE.

Application filed August 2, 1919. Serial No. 315,000.

To all whom it may concern:

Be it known that we, BERNARD LIBERMAN, LEON LIBERMAN and WILLIAM M. REICHART, all citizens of the United States, and all residing at Philadelphia, in the county of Philadelphia and State of Pennsylvania, have invented certain new and useful Improvements in Cigar-Bunching Machines, of which the following is a specification.

10 Our invention relates to cigar bunching machines, that is to say, to machines in which a measured quantity of tobacco is rolled within a binder to form a cigar bunch which is subsequently made into a completed cigar by the addition of the usual wrapper in a subsequent operation. Our present invention relates more particularly to improved mechanism for rolling a measured quantity of tobacco within a binder to 20 form the cigar bunch. The principal object of our present invention is to provide improved mechanism for the above mentioned purpose, which is so constructed and arranged whereby a bunch will be produced 25 which will be smoothly rolled and in which the tobacco will be evenly and uniformly distributed throughout the bunch. A further object of our invention is to improve the details of construction of such machines, 30 to render the same more simple, efficient and certain in their action.

The nature and characteristic features of our invention will be more readily understood from the following description taken 35 in connection with the accompanying drawings forming part hereof, in which:

Figure 1 is a view partly in side elevation and partly in section of a portion of a cigar bunching machine embodying the main features of our present invention;

Fig. 2 is a fragmentary detail view of a portion of the apparatus shown in Fig. 1, but with certain of the parts in a forward operative position;

Fig. 3 is a top or plan view, enlarged, of the bunching table and its associated parts;

Fig. 4 is a longitudinal section of the bunching table taken on the line 4—4 of Fig. 3; and

Fig. 5 is a transverse vertical section thereof taken on the line 5—5 of Fig. 4.

Referring to the drawings, in the particular embodiment of my invention therein

shown, the bunching machine is provided with side-frames 10 upon which the various parts thereof are supported and mounted. The main driving shaft 11 is journaled in suitable pillow blocks 12 which are supported on the side-frames 10. Connecting the side-frames 10 is a cross-bracket 13, to which the bunching table 14 is integrally attached, and from which it projects forward in the front of the machine. The bunching table 14 is provided at the front end thereof with a portion which extends forward as at 15 and then downward as at 16 forming a bracket for the support of the front ends of a pair of slide-rods 17, the rear ends of which are secured in the transversely extending connecting frame 13 above referred to. The rods 17 constitute slide-ways upon which a frame or carriage 18 is slidably mounted and is adapted to be reciprocated thereon.

The frame work or carriage 18 is provided with a rearwardly extending lug 19, to which a connecting rod 20 is pivotally connected. The connecting rod 20 comprises a member 21 at each end thereof which is provided with a suitable ear for making the pivotal connection, and these members 21 are interiorly threaded and engaged by a bolt 22. The ends of the bolt 22 are respectively provided with right and left hand threads, whereby the length of the connecting rod 20 may be varied and thus provide a means of adjustment for varying the final positions, at the front and rear respectively, of the framework or carriage 18. The bolt 22 may be provided with suitable lock-nuts 23 to maintain the connecting rod 20 in its proper adjusted length.

The rear end of the connecting rod 20 is pivotally connected to one arm 24 of a bell crank lever which is pivotally mounted on a shaft 25 which is supported by the side-frames 10 of the machine. The other arm 26 of the bell crank lever is provided at its end with a slot 27 in which a bolt 28 may be adjustably mounted. The bolt 28 forms a means of pivotal connection for a connecting rod 29, the other end of which is pivotally connected, as at 30, to the free end of a lever 31.

The lever 31 is pivotally mounted on a transverse shaft 32 which is suitably sup-

ported by the side-frames 10 of the machine. The lever 31 also carries a cam roller 33, which is engaged by a cam groove 34 of a cam 35 which is mounted on the main shaft 11 and is constrained to rotate in unison therewith. The contour or shape of the cam groove 34 is such as to cause the reciprocation of the framework or carriage 18 at the proper time during each rotation of the main shaft 11, this motion being transmitted from the cam 35 through the medium of the lever 31, connecting rod 29, bell crank lever arms 26 and 24, and the connecting rod 20. It will be noted that the adjustment of the bolt 28 in the slot 27 of the arm 26 of the bell crank lever affords a means for varying the extent of the longitudinal movement of the framework or carriage 18.

The reciprocating framework or carriage 18 is provided on each side with an arm 36, which arms extend upward on each side of the bunching table 14 and have their respective upper ends slotted as at 37. In each slot 37 there is mounted the end of a bolt 38, provided with nuts 39 on each side of the arm 36, whereby said bolt 38 may be vertically adjusted in the slot 37. The bolt 38 constitutes a journal for the bunching roller 40 which is rotatably mounted thereon.

The bunching table 14 is provided with a transverse channel or pocket 41 located immediately forward of the rear position of the bunching roller 40. An apron 42 is also secured to the bunching table 14 at the front and rear respectively. The means for securing the apron at the rear comprises a transverse bar 43 which is attached to the frame 13 by means of screws 44 and serves thereby to clamp the rear end of the apron 42.

The front end of the apron 42 is secured to the forward end of the bunching table 14 by means of a transverse bar 45, which is also attached to the bunching table 14 by means of screws 46. The screws 46 are located beyond the side margins of the apron 42 so that by loosening the same, the front end of the apron 42 which passes beneath the bar 45 may be adjusted to thus vary the size of the rolling pocket which is formed beneath and to the rear of the bunching roller 40 in the usual manner during the operation of the machine.

The apron 42 at the rear is substantially of the full width of the bunching table 14, but at the forward end, that is to say, that portion of the apron which rests on the bunching table proper, is relatively narrow being of a width slightly less than the length of the cigar bunch to be rolled on the table. Arranged on each side of the narrow portion of the apron 42 is a bar 47, which bars extend along the side margins 65 of the narrow portion of the apron 42 and

have inclined upper surfaces (see Fig. 5), these bars 47 constitute means completing the length of the rolling portion of the device, it being noted that the binder of the cigar bunch, co-acting with the apron 42 70 and the bars 47, will tend to shape the bunch to the proper contour and evenly distribute the tobacco therethrough.

The end forming bars 47 are adjustably secured to the top of the bunching table 14 75 by means of bolts 48, which bolts 48 are provided at their lower ends with thumb screws 49, the bolts 48 passing through the slots 50 in the bunching table 14. The slots 50 are arranged transverse to the longitudinal extension of the bunching table 14 to thus permit the end forming bars 47 to be adjusted sidewise to conform to the length of the bunch which is formed on the table 14. The bar 45 which clamps the front end 85 of the apron 42 to the table 14 is provided with a spring-clip 52 which receives and clamps the completed bunch at the end of the forward movement of the roller 40 until the operator has an opportunity to remove the same therefrom.

In order to smooth out the binder as the same is rolled into the bunch, there is provided a brush 60 which, in the rearward position of the reciprocating parts, is located immediately in front of the channel or pocket 41 of the bunching table 14. The brush 60 is provided with a back portion 61 which is adjustably mounted on a transversely extending plate 62, the means of attachment comprising screws 63, which pass through slots 64 in the plate 62. The plate 62 is provided at each end with downwardly depending ears 65 secured to arms 66 as at 67. Each arm 66 is provided at its lower end with a pivot screw 68 which passes through an upwardly inclined slot 69 in an ear 70 extending from the lower portion of the reciprocating carriage 18.

Arranged on each side of the table 14 is a coil spring 71 which is connected at one end to the link 66 at a point midway the extremities of said link, and at its other end to a portion of the reciprocating carriage 18, namely, the upwardly extending arm 36, which is provided on each side of said reciprocating carriage 18 to support the bunch roll 40. On each side of the bunch table 14 adjacent the channel or pocket 41 there is provided an outwardly extending stop-pin 72 which is encountered by the link 66 when the reciprocating carriage 18 is in its rearward position, and serves to retract the brush 60 away from the bunching roll 40 while the tobacco which forms the body 125 of the bunch is being deposited in place.

It may now be noted that the springs 71 serve to cause the brush 60 to contact with the binder at that portion of the apron 42 which is immediately over the bunch roll 40 130

during the forward movement of the reciprocating carriage 18 and the parts carried thereby, this brush 60 as before stated, serving to smooth out the binder during the 5 rolling or bunching operation. In order to regulate the tension with which the end of the brush 60 thus contacts with the apron 42 and the binder arranged thereon, there are provided adjusting screws 75 which are 10 respectively mounted in the upwardly extending arms 36 of the reciprocating carriage 18. The adjusting screws 75 are adapted to be encountered by projecting lugs 76 which are carried by the arms 66 15 at suitable locations.

In bunching mechanism of the general type hereinbefore described, it frequently occurs that during the return movement of the bunching roll, that the bight of the 20 apron will be improperly caught under the rear of the roll 40 and interfere with the proper functioning of the apparatus, particularly when the same constitutes a portion of a complete machine wherein the 25 various parts are co-ordinated with other mechanisms which function at related periods. To prevent the aforesaid improper confining of the bight of the apron under the rear of the roll 40, there is provided a 30 transversely extending bar 80 which is attached by means of arms 81 to the upwardly extending arms 36 of the reciprocating table 18. The bar 80 is located to the rear of the bunching roll 40 a sufficient distance to 35 prevent any portion of the bight of the apron 42 from passing beneath the bunching roller 40 during the rearward moving of the carriage 18.

The operation of the machine will now 40 be readily understood. As before stated, the main shaft 11 makes one complete revolution for each cigar bunch formed by the machine. As the shaft 11 rotates, after the cam 35 arrives at the proper angular location, the lever 31 will thereby be actuated, causing the outer end thereof to be depressed and, through the intermediary of the connecting rod 29, bell crank lever arms 45 26 and 24, and connecting rod 20, the carriage 18 will be moved forward on the slide-ways formed by the rods 17. In this manner, the roller 40 which is carried by the arms 36 of the carriage 18 will be moved forward over the table 14.

55 However, previous to the forward movement of the bunching roller 40, the binder will have been deposited over the brush, and so as to project partly upon the apron 42, immediately over the channel 41. A 60 measured quantity of tobacco which is to constitute the filler of the bunch is also deposited upon the apron and upon the projecting end of the binder. As the filler is deposited, either manually or by means of 65 other mechanism, the construction of which

forms no part of the present invention however, the apron 42 is depressed into the channel 41 of the bunching table 14.

It will be seen that as the roller 40 advances over the table 14, the portion of the 70 apron which contains the filler and a projecting end of the binder will be caught in a bight which will be formed beneath and to the rear of the bunching roller 40, and as the roller continues to advance over the 75 table 14, the filler and binder will be rolled to the completed bunch which will thereafter be deposited in the spring clip 52 which is provided at the front end of the bunching table 14.

80 During the first part of the forward movement of the bunching roller 40, the brush 60 will be given a relative rearward movement towards the bunching roller 40, carrying a part of the binder which lies over it into close proximity to the bunching roller 40. The rearward movement of the brush 60 towards the roller 40 is caused by the tension of the springs 71 which will 85 cause the pivot screws 68 carried at the lower ends of the arms 66 to slide in the upwardly inclined slots 69 of the lugs or ears 70, and, when the pivots 68 reach the end of said slots, the upper portion of the arms 66 which carry the brush 60 will then 90 be swung towards the roller 40. This causes a slight elevation and tilting of the brush towards the roller. The tension with which the brush 60 will press against the binder is limited or regulated by means of the adjusting screws 75 which are carried by the arms 36 and which are encountered by the 95 lugs 76 carried by the arms 66.

100 As before stated, the rear portion of the apron 42 is of substantially the full width of the bunching table, while the forward portion thereof is of a width somewhat less than the length of the bunch which is formed on the table. In connection with the narrow portion of the apron 42, the 105 plates 47 are provided which as before stated, have inclined upper surfaces which co-act with the ends of the binder which extend beyond the side margins of the narrow portion of the apron. The plates 47 110 serve to prevent length-wise sliding of the filler within the bunch and will maintain the proper tapered shape of the ends of the bunch.

115 After the bunch has been rolled and deposited within the spring-clip 52, the carriage 18 will then start on its rearward movement, and when the links 66 which carry the brush 60 encounter the pins 72, the brush 60 will thereby be raised away 120 from the bunching roller 40 as the same continues to pass to its rearward position.

125 The apron 42 is made of the usual flexible material, and as the roller 40 in its movement to the rear passes over the chan- 130

nel 41 there will ordinarily be a tendency of the apron to be improperly caught beneath the roller 40, which action would subsequently interfere with the proper functioning of the machine. To overcome this difficulty, the bar 80 is provided, the same extending transversely some distance to the rear of the roller 40, and raised sufficiently above the rear portion of the table to enable the apron 42 to be freely released from under the same. When the carriage 18 is in its rearward position, the transversely extending bar 80 will also serve to temporarily maintain the apron 42 above the channel 41 so that the binder may be more readily positioned thereon by the operator of the machine.

Having thus described the nature and characteristic features of our invention what we claim as new and desire to secure by Letters Patent is:

1. In a cigar bunching machine, the combination of a bunch-rolling table, an apron and cooperating roller, a reciprocating roller support, a brush for cooperating with the apron, in rolling the binder on the bunch, means for automatically positioning the brush and roller a required distance apart to permit depositing the filler between them, means for actuating the brush to cause its movement toward the roller during preliminary movement of the roller and adjustable means for limiting said actuation.

2. In a cigar bunching machine, the combination of a bunch-rolling table, an apron and cooperating roller, a reciprocating roller support, and an apron engaging bar extending parallel with the roller and to the rear thereof and movable with the reciprocating roller support.

3. In a cigar bunching machine, the combination of a bunch-rolling table, an apron and cooperating roller, a reciprocating roller support, a brush for cooperating with

the apron in rolling the binder on the bunch, means for automatically positioning the brush and roller a required distance apart to permit depositing the filler between them, and means for automatically actuating the brush to move toward the roller simultaneously with the preliminary movement of the roller, and adjustable means for limiting said brush actuation, and for maintaining an adjusted relationship between brush and roller when moving together.

4. In a cigar bunching machine, in combination with the usual bunch rolling table, apron, cooperating roller and reciprocating roller support, a brush for cooperating with the apron, brush-supporting arms having pin and slot connection with the reciprocating support and spring controlled, a stop on the stationary table and an adjustable stop on the reciprocating support for engaging a brush supporting arm, one stop effective in certain positions of the reciprocating support and the other stop effective in other positions of said support.

5. In a cigar bunching machine, in combination with the usual bunch rolling table, apron, cooperating roller and reciprocating roller support, a brush for cooperating with the apron, brush-supporting arms having pin and upwardly inclined slot connection with the reciprocating support and spring controlled, a stop on the stationary table and an adjustable stop on the reciprocating support for engaging a brush supporting arm, one stop effective in certain positions of the reciprocating support and the other stop effective in other positions of said support.

In testimony whereof we have hereunto signed our names.

BERNARD LIBERMAN.
LEON LIBERMAN,
WILLIAM M. REICHART.
